(57) **CLAIM**

The ornamental design for a soap dispenser, as shown and described.

DESCRIPTION

FIG. 1 is a front elevational view of a soap dispenser showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective plan view thereof; and,

FIG. 8 is a cross-sectional view thereof along the 8-8 line shown in FIG. 1;

The even dashed broken lines show portions of the article that form no part of the claimed design. The uneven dashed broken lines show boundaries that form no part of the claimed design.

1 Claim, 3 Drawing Sheets
